UNITED STATES PATENT OFFICE.

JOHN E. BOLLING, OF NEW YORK, N. Y., ASSIGNOR TO CARRIER ENGINEERING CORPORATION, OF NEW YORK, N. Y.

DESIGN FOR A PAPER-HOLDER.

55,547.

Specification for Design.

Patented June 29, 1920.

Application filed November 5, 1919. Serial No. 335,948. Term of patent 7 years.

To all whom it may concern:

Be it known that I, JOHN E. BOLLING, a citizen of the United States, residing at New York, in the county of New York and State of New York, have invented a new, original, and ornamental Design for Paper-Holders, of which the following is a specification.

In the accompanying drawings:

Figure 1 is a perspective view of a paper holder embodying the design.

Fig. 2 is a top plan view thereof.

I claim:

The ornamental design for a paper holder as shown.

JOHN E. BOLLING.
